UNITED STATES PATENT OFFICE.

FRANK J. MATCHETTE AND RICHARD RADDATZ, OF MILWAUKEE, WISCONSIN, ASSIGNEES, BY MESNE ASSIGNMENTS, TO RICHMOND RADIATOR COMPANY, OF NEW YORK, N. Y., A CORPORATION OF DELAWARE.

VACUUM CLEANING AND FORCE-DRAFT SYSTEM.

1,224,482.

Specification of Letters Patent.

Patented May 1, 1917.

Original application filed March 2, 1905, Serial No. 248,106. Divided and this application filed September 30, 1910. Serial No. 584,586.

To all whom it may concern:

Be it known that we, FRANK J. MATCHETTE and RICHARD RADDATZ, citizens of the United States, residing at Milwaukee, in the county 5 of Milwaukee and State of Wisconsin, have invented certain new and useful Improvements in Vacuum Cleaning and Force-Draft Systems, (Case B,) of which the following is a specification, reference being had to the 10 accompanying drawing, forming a part thereof.

This invention relates to apparatus designed to remove dust and dirt from floors, 15 walls and other surfaces and from carpets, furniture or the like, by means of a current of air.

The main object of the present invention is to utilize the exhaust from such a system for accelerating the draft and promoting 20 combustion in a furnace or the like.

It consists in the construction, arrangement and combination of parts as herein-after particularly described and pointed out 25 in the claims.

25 In the accompanying drawing like characters designate the same parts in both figures.

Figure 1 is a side elevation partly in section, showing a stationary plant embodying the invention; and Fig. 2 is a similar view showing certain features of the invention as embodied in portable apparatus.

Referring to Fig. 1, a piping system is shown, comprising a suction or service main 35 a , and one or more branches b , having valve controlled inlet or service connections c on the several floors or in the different apartments of the building for the attachment of suitable vacuum or suction tools or cleaners, 40 which are not shown.

A stationary steam boiler d mounted in an ordinary brick setting and provided with a smoke stack or escape flue e , is usually located in the basement of the building. Below 45 the boiler the brick setting forms the usual furnace, comprising a combustion chamber f above, and an ash pit g below, the grate i .

The suction or service main a preferably 50 leads into a primary dust collector or separator j , which is preferably located in the basement of the building or near the furnace, so as to remove from the air the heavier

and coarser particles of dirt and thus prevent them from clogging or interfering with 55 the operation of the aspirator or vacuum producing means hereinafter mentioned. The primary dust collector or separator j is connected by an eduction pipe k with a secondary dust collector or separator l . In 60 this pipe is located an aspirator or ejector m , which is connected by a pipe n with the boiler d or the steam supply main o leading therefrom. The pipe n is provided with a valve p for manually shutting off the supply 65 of steam to the aspirator and also with an automatic regulating valve q operated by a diaphragm or similar device, indicated at r , and connected on one side by a pipe s with the pipe k or any other convenient part 70 of the system in which vacuum or low service pressure is maintained, the valve q and its actuating device r with their connections constituting an automatic controller or regulator. 75

From the lower part of the secondary dust collector or separator l , a discharge pipe t provided with a valve u , leads through the wall of the furnace above the grate i into the combustion chamber f . From the upper part 80 of said dust collector or separator leads another pipe v having a valve w and a three-way valve x , with one branch of which is connected a blast nozzle y in the smoke stack e of the boiler furnace, while with the other 85 branch is connected a blast nozzle z in a ventilating flue, waste conduit or other duct 2, for producing a draft therein. Still another pipe 3 provided with a valve 4 and with a three-way valve 5 , leads from the 90 dust collector or separator l at a point above which dust and dirt are allowed to accumulate therein. One branch of the three-way valve 5 is connected with the ash pit g below the grate i of the furnace by a pipe 6 , 95 while the other branch is connected by a pipe 7 with a feed water or other heating device, represented by a radiator 8 .

The apparatus as thus far described, may be operated in several different ways. If it 100 be desired to discharge the exhaust from the aspirator m directly into the furnace, the valves w and 4 are closed and the valve u is opened, whereupon the mingled air, steam and dust issuing from the aspirator are directed into the combustion chamber f of the 105

furnace above the grate g , accelerating the draft of the furnace and promoting combustion of the fuel therein, besides disposing of the dust and dirt in a convenient, 5 harmless and inoffensive manner. Or, if desired, the valve u may be closed and the valve w opened, whereupon the air and steam from which dust and dirt are removed in the dust collector or separator l , pass 10 through the pipe v and are discharged from the blast nozzle y into the smoke stack or escape flue e , or are discharged from the blast nozzle z into the duct 2 , according to the position of the valve x .

15 On the other hand, by closing the valves u and w and opening the valve 4 , the air and steam from which dust and dirt have been removed in the collector or separator l , may be discharged through the pipe 6 into the ash pit g of the furnace, thus tending 20 to cool the grate bars and soften clinkers, as well as acting to accelerate the furnace draft and aid combustion. Or by the proper manipulation of the valve 5 the exhaust 25 steam and air from the aspirator may be directed through the pipe 7 into the radiator 8 or other heating device, in which the otherwise waste heat of the steam is advantageously utilized without affecting the operation 30 or impairing the efficiency of the cleaning apparatus. During the operation of the apparatus in the various ways last described, when the exhaust steam and air are directed into the smoke-stack e , duct 2 , 35 ash pit g or heater 8 , the dust accumulating in the collector or separator n is discharged from time to time by opening the valve u .

Referring to Fig. 2 showing portable apparatus embodying certain features of the 40 invention, the vacuum piping system is represented by a flexible pipe or hose a' with which the cleaning tool is connected. d' is a portable vertical fire tube boiler having a smoke stack or escape flue e' , an internal 45 fire box or combustion chamber f' , ash pit g' and grate i' . In this case the secondary dust collector l is omitted and the eduction pipe h is provided at its discharge end with a three-way valve 9 , one branch of which is 50 connected by a pipe 10 with a blast nozzle 11 in the smoke stack e' , while the other branch is connected by a pipe 12 with another three-way valve 13 , from which branch pipes or nozzles 14 and 15 lead into the 55 combustion chamber f' and ash pit g' above and below the grate i' respectively. Each of the branch pipes 14 and 15 may be surrounded at its discharge end by a cone or tube 16 for entraining into the furnace with 60 the exhaust jet, additional air.

The operation of this portable form of apparatus is similar to that of the stationary apparatus hereinbefore described, the mingled steam, air and dust being discharged 65 either into the ash pit, combustion chamber

or smoke stack of the furnace, as may be found desirable for producing the best results under varying conditions. The dust collector or separator j may in this case be constructed to remove all or most of the 70 dust from the air, so that the discharge of the exhaust from the aspirator into the open air will be unobjectionable.

Various modifications in the construction and arrangement of the several parts of the 75 apparatus may be made without departing from the scope of the invention.

Features shown and not claimed herein are claimed in our co-pending applications Serial Nos. 584,585 and 584,587. 80

We claim:

1. In a vacuum cleaning and force draft system, in combination, a piping-system having means for receiving material to be conveyed thereby, a steam ejector or aspirator 85 in communication with a pressure supply and adapted to draw air and dust through said system, a steam-generator, including a furnace, adapted to supply steam to said aspirator for operating it, a chamber into 90 which said aspirator discharges dust, a discharge pipe leading from said chamber to supply the dust to said furnace, and an independent discharge from said chamber for the air discharged through said aspirator 95 arranged as a draft nozzle in the exhaust-flue or stack of said steam-generator.

2. In a vacuum cleaning and force draft system, in combination, a piping-system having means for receiving material to be conveyed thereby, a steam ejector or aspirator in combination with a pressure supply and adapted to draw air and dust through said system, means actuated by a change of the pressure in said system for automatically 100 controlling said ejector, a steam-generator, including a furnace, adapted to supply steam to said aspirator for operating it, a chamber into which said aspirator discharges dust, a discharge pipe leading from said chamber 105 to supply the dust to said furnace, means for controlling said discharge pipe, and an independent discharge from said chamber 110 leading under the fire in said furnace.

3. In a device of the class described, a 115 piping system having means for receiving material to be carried thereby, an aspirator in communication with a pressure supply for actuating the same and designed to draw air and dust through said system, a fuel burning device, said aspirator being arranged to discharge the air and dust from the system into the fuel burning device and means controlled by the air pressure in said system for regulating said aspirator. 120

4. In a device of the class described, a piping system having means for receiving material to be carried thereby, an aspirator in communication with a pressure supply for actuating the same and designed to draw air 130

and dust through said system, a fuel burning device, said aspirator being arranged to discharge the air and dust from the system into the fuel burning device, a valve for controlling the admission of pressure fluid to said aspirator, and an automatic controller operatively connected with said valve and piping system.

In witness whereof we hereto affix our signatures in presence of two witnesses.

FRANK J. MATCHETTE.
